ELECTRON DISCHARGE DEVICE

Filed Jan. 22, 1929

FIG.1

FIG. 2.

FIG. 3.

Inventor
SAMUEL RUBEN

By his Attorney M. W. Chapman

UNITED STATES PATENT OFFICE

SAMUEL RUBEN, OF NEW YORK, N. Y., ASSIGNOR, BY MESNE ASSIGNMENTS, TO RUBEN TUBE COMPANY, OF ENGLEWOOD, NEW JERSEY, A CORPORATION OF DELAWARE

ELECTRON DISCHARGE DEVICE

Application filed January 22, 1929. Serial No. 334,346.

This invention relates to an electron discharge device and more particularly it relates to a vacuum discharge device in which the electron stream is controlled by an electro-
5 magnetic field.

The use of a magnetic field to control an electron discharge is known to the prior art; but by those means the control is limited and various other restrictions prevail. By my in-
10 vention the arrangement and combination of elements and the method of their application, a means is provided by which the limitations referred to are eliminated and an electron stream response is obtained that is sensitive
15 to magnetic fields of low intensity.

The fundamental requirements for such sensitive response are internal armature plates providing a constricted electron stream path and an electrostatically shielded plate
20 element.

For a better understanding of the invention reference is made to the accompanying drawing showing an embodiment thereof, in which

Fig. 1 illustrates an electron discharge tube
25 having in addition to the usual elements, internal magnetic armature plates, Fig. 2 showing in section a plan view of the tube elements taken on the line of 2—2 of Fig. 1 and Fig. 3 is diagrammatically illustrative of the device
30 with the external magnetic fields, arranged in an electric circuit to which the invention is applicable.

The arrangement of the cathode, grid and plate is such that the plate is electrostatically
35 shielded by the grid; also by this arrangement the impedance of the plate circuit is reduced. In addition, within the tube, highly evacuated to obtain a pure electron discharge, are two magnetically conductive plates separated
40 by a narrow gap.

Referring more particularly to Fig. 1, E represents a glass envelope containing in a high vacuum, filamentary cathode 1, and grid 3, which electrostatically shields anode 4. At
45 5 are arranged armature plates of a magnetic material, such as nickel-steel or pure iron, separated from each other by narrow gap 5a. Like numerals are employed in Figs. 2 and 3 to represent corresponding elements. In Fig.
50 3, 6 represents two external magnetic arma-

tures and in the circuits B is a source of potential for energizing cathode 1, B₁, a source of potential for accelerating the electron discharge to the grid and plate elements. At M is a micro-ammeter to indicate the plate current and at 7 is a bar of magnetic material, to be tested for its permeability. 55

In the operation of the magnetic tube as shown by the arrangement of Fig. 3, when the filament, grid and plate are sufficiently energized there is an electron flow from the filament through gap 5a to the grid 3 and plate 4, the meter M, indicating the plate current. The armatures 5 are magnetized by the external magnetic field and the electron 65 stream is diverted from its path to a degree determined by the intensity of the field, the space charge being increased, with a corresponding reduction of the plate current. This current is reduced to zero when a field of 70 sufficient intensity is applied. By the use of the external magnetic armatures 6, armatures 5, are energized thereby.

In Fig. 3 the external armatures 6, are bridged by a bar of magnetic material 7, 75 which affords a path of lower reluctance for the external magnetic field and effects a reduction of the plate current, the reduction varying with the permeability of the bar.

By the use of the shielding grid 3, the 80 plate current change for a given magnetic field variation in the armature is many times increased, thus producing extreme sensitivity of response in the plate current to field intensities of low values. This effect is comparative with that from an electrostatically 85 operated shield grid tube in which relatively large plate current changes occur with a low potential on the control grid.

This device is applicable to many uses such as magnetic compass, motion indicator, audio-frequency amplifier, etc.

What I claim is:

1. An electron device comprising, in combination, an evacuated envelope, a cathode, a grid, an electrically shielded anode and magnetic armatures, the armatures being located in a plane between the cathode and anode and spaced apart by a gap between the cathode and anode. 95

8. 2. An electron device comprising, in combination, an evacuated envelope, a cathode, a grid, an electrically shielded anode and magnetic armature plates the plates being located in a plane and spaced apart by a gap between the cathode and anode, and means for magnetically energizing said armatures.
- 10 3. An electron device comprising, in combination, an evacuated envelope, a cathode, a grid, an electrically shielded anode and magnetic armature plates, said plates being located in a plane and spaced apart by a gap between the cathode to the anode, and externally mounted magnetic armatures.
- 15 4. An electron device comprising, in combination, an evacuated envelope, a cathode, a grid, an anode, the anode being electrically shielded by the grid and magnetic armatures, said armatures being located in a plane between the cathode and the anode and spaced apart by a gap between the cathode to the anode, and magnetic armatures mounted externally of the envelope.

In testimony whereof, I, SAMUEL RUBEN,
25 have signed my name to this specification this
21st day of January, 1929.

SAMUEL RUBEN.
